UNITED STATES PATENT OFFICE.

ALBERT E. SEHLBACH, OF CHICAGO, ILLINOIS, ASSIGNOR TO ALBERT PICK & COMPANY, OF CHICAGO, ILLINOIS, A CORPORATION OF ILLINOIS.

DESIGN FOR A GOBLET OR SIMILAR ARTICLE OF GLASSWARE.

57,933.

Specification for Design.

Patented May 17, 1921.

Application filed August 16, 1920. Serial No. 403,947. Term of patent 7 years.

To all whom it may concern:

Be it known that I, ALBERT E. SEHLBACH, a citizen of the United States, residing at Chicago, in the county of Cook and State of Illinois, have invented a new, original, and ornamental Design for a Goblet or Similar Article of Glassware, of which the following is a specification, reference being had to the accompanying drawing, forming a part thereof.

The figure is a side elevation of a goblet or similar article of glassware embodying the new border design.

I claim:

The ornamental design for a goblet or similar article of glassware as shown.

ALBERT E. SEHLBACH.
